(57) **CLAIM**

The ornamental design for a penile sleeve implant, as shown and described.

DESCRIPTION

FIG. 1 is a top, isometric view of a first embodiment of a penile sleeve implant showing my new design;

FIG. 2 is a right side elevation view of the penile sleeve implant of FIG. 1;

FIG. 3 is a left side elevation view of the penile sleeve implant of FIG. 1;

FIG. 4 is a top, plan view of the penile sleeve implant of FIG. 1;

FIG. 5 is a bottom, plan view of the penile sleeve implant of FIG. 1;

FIG. 6 is a front, elevation view of the penile sleeve implant of FIG. 1; and,

FIG. 7 is a back, elevation view of the penile sleeve implant of FIG. 1.

The features shown in broken lines in the drawing depict portions of the design that form no part of the claimed design.
